[57] CLAIM

The ornamental design for a covered pitcher or the like, as shown and described.

DESCRIPTION

FIG. 1 is a top, front perspective view of a covered pitcher or the like showing a first embodiment of our new design;

FIG. 2 is a front elevational view of FIG. 1;

FIG. 3 is a rear elevational view of FIG. 1;

FIG. 4 is a right side elevational view of FIG. 1;

FIG. 5 is a left side elevational view of FIG. 1;

FIG. 6 is a top plan view of FIG. 1;

FIG. 7 is a top bottom view of FIG. 1;

FIG. 8 is a top, front perspective view of a second embodiment of our new design for a covered pitcher or the like;

FIG. 9 is a front elevational view of FIG. 8;

FIG. 10 is a rear elevational view of FIG. 8;

FIG. 11 is a right side elevational view of FIG. 8;

FIG. 12 is a left side elevational view of FIG. 8;

FIG. 13 is a top plan view of FIG. 8;

FIG. 14 is a bottom plan view of FIG. 8;

FIG. 15 is a cross-sectional view taken along line 15—15 of FIG. 6;

FIG. 16 is a cross-sectional view taken along line 16—16 of FIG. 6;

FIG. 17 is a cross-sectional view taken along line 17—17 of FIG. 13; and

FIG. 18 is a cross-sectional view taken along line 18—18 of FIG. 13.
